Primary Examiner — Prabhakar Deshmukh

(74) Attorney, Agent, or Firm — Choate Hall & Stewart LLP; William R. Haulbrook

(73) Assignee: **Physical Apps, LLC**, Hollis, NH (US)

(57) **CLAIM**

The ornamental design for a physical interaction device for personal electronics, as shown and described.

(***) Term: **14 Years**

DESCRIPTION

(21) Appl. No.: **29/443,736**

FIG. 1 is a perspective view of a physical interaction device for personal electronics showing my new design;

(22) Filed: **Jan. 22, 2013**

FIG. 2 is a top view thereof;

(51) LOC (10) Cl. 21-01

FIG. 3 is a bottom view thereof;

(52) U.S. Cl.

FIG. 4 is a right side view thereof;

USPC **D21/300**; D23/333

FIG. 5 is a left side view thereof;

(58) **Field of Classification Search**

FIG. 6 is a front view thereof;

USPC D21/324-333, 499, 695, 386, 398;

FIG. 7 is a rear view thereof;

273/188-291, 153 R, 148 B, 458;

FIG. 8 is a perspective view of a second embodiment of a physical interaction device for personal electronics:

446/85, 119, 121, 124, 267; 482/142,

FIG. 9 is a top view thereof;

482/143; D6/349, 329

FIG. 10 is a bottom view thereof;

See application file for complete search history.

FIG. 11 is a right side view thereof;

(56) **References Cited**

FIG. 12 is a left side view thereof;

U.S. PATENT DOCUMENTS

FIG. 13 is a front view thereof;

3,666,269 A * 5/1972 Gilchrist 273/115

FIG. 14 is a rear view thereof;

3,841,039 A * 10/1974 Farnsworth, III 52/81.1

FIG. 15 is a cross sectional view of a top half thereof; and,

D284,493 S * 7/1986 King D21/713

FIG. 16 is a cross sectional view of a bottom half thereof.
